(57) CLAIM

The ornamental design for a shoe, as shown and described.

DESCRIPTION

FIG. 1 is a front perspective view of a shoe showing my new design;

FIG. 2 is a front view thereof; and,

FIG. 3 is an opposite side front perspective view thereof. The lighter grey portions are for the purpose of illustrating portions of the shoe which form no part of the claimed design.

1 Claim, 3 Drawing Sheets

FIG. 1

FIG. 3
